UNITED STATES PATENT OFFICE.

ARNO SHUMAN, OF PHILADELPHIA, PENNSYLVANIA, ASSIGNOR TO PENNSYLVANIA WIRE GLASS COMPANY, OF PHILADELPHIA, PENNSYLVANIA, A CORPORATION OF NEW JERSEY.

ROOF OR SKYLIGHT CONSTRUCTION.

Application filed December 20, 1924. Serial No. 757,089.

The present invention relates more particularly to roof or skylight construction for corrugated glass, either wire or plain, but in some of its aspects it may include the use 5 of flat glass.

The principal objects of the present invention are to provide a roof or skylight construction which can be installed or repaired from the outside or top without requiring 10 the erection of scaffolding inside or beneath the roof or skylight construction; to provide a roof or skylight construction of which the parts can be made or fabricated at a shop or factory leaving only the work of assembly 15 to be done on the job; to provide in the structure of the roof or skylight construction a deformation of the skylight or roof bar which gives rise to a wedging effect that provides and insures stability; to provide in the 20 roof or skylight construction an adjustment adapted to compensate for irregularities, if any, in the alignment of the purlins; and to facilitate and cheapen the installation and construction of a roof or skylight.

25 The invention comprises the improvements to be presently described and finally claimed.

In the following description reference will be made to the accompanying drawings forming part hereof and in which there is shown 30 an embodiment of the invention selected from among other embodiments for the sake of illustration, and in the drawings

Figure 1 is a sectional view taken crosswise of the purlins and illustrating roof or 35 skylight construction embodying features of the invention.

Fig. 2 is a top or plan view of a portion of the roof or skylight construction embodying features of the invention with the glass 40 and weather stripping omitted.

Fig. 3 is a transverse sectional view taken crosswise of the purlins, drawn to an enlarged scale, and illustrative of a complete roof or skylight construction embodying features of the invention.

Fig. 4 is a sample transverse sectional view taken parallel with the purlins, and

Fig. 5 is a sectional view taken generally on the line 5—5 of Fig. 3 looking upward 50 and illustrating in an exaggerated degree the deformation of a roof or skylight bar.

In the drawings 1 are purlins, and 2 indicates rafters or rafter-like supports for the purlins. 3 are roof or skylight bars arranged on top of the purlins and they are

shown as angle bars or, more specifically, bars of V-shape in cross-section and they are disposed with their gutter faces confronting the purlins and their ridge faces arranged upward. 4 are slip shackles embracing the free or gutter edges of the walls of the bars. 5 are clamp plates of which the tails 6 engage the purlins and which are provided with upturned toes 7 taking into the gutters of the bars. The toes 7 are shown as of blunt wedge shape to conform to the cross-section of the bars 3. 8 are carriage bolts, meaning bolts with squared shanks, interposed between the plates 5 and shackles 4 and operating to cause the plates and shackles in co-operation with the purlins to deform the bars as generally indicated at *a* in Fig. 5, and insure endwise stability of the bars in the direction of the eaves as indicated at *b* in Fig. 1. 9 and 10 are sheets of glass resting on top of the purlins with their margins spaced apart at the bars, as indicated at 11 in Fig. 4. The sheets of glass are shown as corrugated. While two sheets in overlapping relation at or near the purlins have been referred to, more than two sheets may be employed as in the case of large roofs and only one sheet may be employed as in the case of small skylights, referring of course to the rafter direction of the roof and as many sheets may be employed in the purlin direction of the roof as may be required. 12 are metal strips overlying the adjoining margins of the glass sheets and covering the bars 3, and these strips are provided with hooked ends or toes 13 engaging the eave edges of the sheets. Felt or the like 14 may be interposed between the metal strips and the sheets of glass. 15 are screws disposed at intervals which may be regular and they penetrate the strips and have their pointed shanks engaging the bars 3, or more accurately, tapped holes provided in the ridges thereof. 16 are washers that may be interposed between the heads of the screws 15 and the strips 12.

The bars 3 may be provided with the equally spaced tapped holes at the shop and the clamps and the screws 15 and the washers and strips may also be prepared or manufactured in advance of assembly. In assembling the construction the skylight or roof bars 3 are laid on top of the purlins and workmen from the outside or top of the roof apply the clamps to the purlin flanges. The

shackles 4 are slipped onto the bars with the carriage bolts and clamp plates 5 connected with them. Inasmuch as the clamps as a whole are movable along the bars the clamps 5 can be positioned in engagement with the flanges of the purlins even though the latter are somewhat out of alignment or are not straight, and this can be done by workmen on top of the roof. The workmen may then 10 tighten the carriage bolts thus drawing up the clamps and more or less deforming the bars as has been described so that the bars are held firmly in position to support the weight of the glass against movement in the 15 direction of the eaves. The glass is then laid and the weather strips applied along with the washers 16 and screws 15. Inasmuch as the screws 15 are pointed they can be readily inserted into the tapped holes in 20 the bars nearest to the eaves. Since the holes in the weather strips and in the bars are spaced alike it is quite easy to apply the rest of the screws along the bars from the outside or top of the roof. Evidently the 25 clamps hold the bars against movement in respect to the eaves and the bars hold the strips which in turn hold the glass, so that the finished construction is firm and well held together. At the same time the elements of the construction during its installation are sufficiently movable to permit of proper alignment of the edges of the glass at the eaves although the purlins may not be quite straight. From the foregoing description 30 it is evident that no scaffolding is required for the erection of the roof or skylight and in that way a very material economy is effected. Of course no scaffolding is required for the renewal of glass since such 35 renewal can be effected from the outside of the roof because the screws 15 are readily accessible.

By way of further explanation of Fig. 4, it may be said that the screw 15 at the top of the figure may be considered to be the 45 screw 15 shown in Fig. 3, and the screw 15 shown at the intermediate portion of the height of Fig. 4 may be said to be a screw 15 not shown in Fig. 3 but which would appear at the next space toward the left if Fig. 3 50 were continued beyond the confines of the sheet.

It will be obvious to those skilled in the art to which the invention relates that modifications may be made in details of construction and arrangement and in matters of mere form without departing from the spirit of the invention which is not limited to such matters or otherwise than as the prior art and the appended claim may require. 55

I claim:

A skylight and roof construction including purlins, V-bars arranged on top and crosswise of the purlins with their gutter 65 faces confronting the purlins, slip shackles embracing the free edges of the gutter walls of the bars, clamp plates of which the tails engage the purlins and which are provided with upturned blunt-wedge toes taking into 70 the gutters of the bars, carriage bolts interposed between the plates and shackles and operative to cause deformation of the bars, sheets of corrugated glass resting on the purlins with their margins spaced apart at 75 the bars, metal strips overlying the adjoining margins of the sheets and covering the bars and provided with toes engaging the eave edges of the sheets, and pointed screws disposed at regular intervals and penetrating 80 the strips and engaging tapped holes provided in the ridge faces of the bars. 85

ARNO SHUMAN.
